UNITED STATES PATENT OFFICE

168,391

DISPLAY HOLDER FOR LETTERING PENS
OR SIMILAR ARTICLES

Gladys H. Benedict, Denver, Colo.

Application September 4, 1952, Serial No. 21,335

Term of patent 14 years

(Cl. D80—9)

To all whom it may concern:

Be it known that I, Gladys H. Benedict, a citizen of the United States, residing at Denver, State of Colorado, have invented a new, original, and ornamental Design for Display Holder for Lettering Pens or Similar Articles, of which the following is a specification, reference being had to the accompanying drawing, forming a part hereof.

I claim:

The ornamental design for a display holder for lettering pens or similar articles, as shown.

GLADYS H. BENEDICT.
